ABSTRACT

Apparatus for cleaning interior walls of a sectionalized drill stem of a rotary drill, the drill having a rotating drilling head to which sections of a drill stem can be secured, the apparatus having a scraper having a sliding fit in a clean drill stem and secured by a cable from the drilling head so that when, during a drilling operation, the drill head is disconnected from an upper end of the drill stem and lifted to add a new drill stem section the scraper is automatically drawn upwards through the upper section of the drill stem so as to scrape the walls of the latter.

DRILL STEM CLEANER

BACKGROUND OF THE INVENTION

1. Field of the Invention

This invention relates to apparatus for cleaning interior walls of a drill stem of a rotary drill during a drilling operation.

2. Prior Art

The propensity of drill stems of rotary drills to become encrusted with rock chips, mud and the like to a point where passage of an overshot for lifting core tubes is hindered. This is especially so in rotary drills used in mining exploration where exploratory drilling is carried in soft rock, or coal, or where mud or sand is encountered.

During a drilling operation, it is common practice when adding a new section of drill stem, to examine the upper section of drill stem in the hole to ascertain whether or not the drill stem requires cleaning, a cleaning tool of type then being manually thrust into the stem to scrape the latter of any accumulation of rock chips and mud. This is arduous and time consuming and is sometimes not carried out resulting in over-buildup of encrustation.

SUMMARY OF THE INVENTION

The present invention provides drill stem cleaning apparatus which automatically scrapes the walls of an upper section of a drill stem whenever a drilling head is disconnected from a drill stem to add new section of 30 drill stem.

The cleaning apparatus of the present invention furthermore does not require manual operation as it is drawn through the drill stem when the drill head is hoisted away from the drill stem. Failure to clean the drill stem, whether accidental or deliberate, is therefore avoided.

The cleaning apparatus of the present invention includes a substantially tubular scraper normally having a sliding fit in a clean drill stem section, a cable connecting the scraper and the drill head for suspending the scraper inside an upper drill stem section so that when the drill stem is disconnected and hoisted away from the upper section of the drill stem to add a new stem section the scraper is automatically pulled upwards through the upper section of the drill stem so as to clean the walls thereof.

DESCRIPTION OF THE DRAWINGS

FIG. 1 is a central sectional view of portion of a drill stem showing the cleaning apparatus of the invention inserted therein, 50

FIG. 2 is a section on 2-2 of FIG. 1,

FIG. 3 is a perspective view of a scraper, a portion thereof being moved for the purpose of clarity of illustration.

DETAILED DESCRIPTION

FIG. 1

FIG. 1 shows an upper portion of a sectionized drill stem, generally 10, an upper section 10.1 of which is connected to a drill head 11, the latter being rotatably driven by conventional and well known means and which has a fluid passage 12 opening at one end 13 into the drill stem through which drilling fluid is pumped by conventional and well known means. The fluid travels through the drill stem and is discharged through a drill

2

bit, not shown, so as to carry rock chips and the like from the face of the drill hole and upwards where it is re-circulated through the drill head and into the drill stem.

5 Due to rotation of the drill stem during a drilling operation the rock chips, mud and the like in the recirculated drilling fluid, and which are normally heavier than the drilling fluid, are thrown radially outward and cling to the walls of the drill stem gradually building up a 10 crust 15, the crust being relatively thick adjacent an upper end of upper section 10.1. If the crust is not removed effective inside diameter of the drill stem is so reduced as to materially hinder passage of an overshot for retrieving, in a known manner, a core tube.

15 Cleaning apparatus generally 18, as shown in FIG. 1, is connected to the drill head 11. The cleaning apparatus includes a cylindrical tubular scraper 19, see FIGS. 1, 2 and 3, having an outside diameter a little less than inside diameter of a drill stem so as to have a sliding fit therein. The scraper is bevelled at its upper end to provide a knife edge 22 and has a connecting bar 23 extending diametrically thereacross.

A cable 24 is looped at one end around the bar 23 and secured by clamps 25. The cable is also looped 20 about and secured to a connecting bar 26 of the drilling head by clamps 27.

Length of cable is such that with the drilling head 11 secured to the drill stem section 10.1 the scraper is disposed just above the lower end 28 of the section 10.1.

25 A screen 29, see FIG. 1, is secured adjacent a lower end of the scraper. The screen has openings large enough to enable rock chips circulated with the drilling fluid to pass through the drill stem during a drilling operation.

OPERATION

30 During a drilling operation the cleaning apparatus which is secured to the drilling head as herein described remains inside the upper drill stem section. Due to its tubular configuration it offers little resistance to the passage of drilling fluid therethrough.

35 When the drill stem has been advanced sufficiently to require addition of a new drill stem section the drilling head is detached from the upper drill stem section and hoisted. The scraper is thus moved upwards through the upper drill stem section 10.1 so as to scrape the walls thereof and remove the crust 15 which is retained on the screen 29 for disposal when the scraper is pulled clear of the drill stem section 10.1. The scraper is then inserted into the new drill stem section and drilling recommenced.

40 It is seen that cleaning of the drill stem is an automatic operation as the cleaning apparatus is never detached from the drill head so that the upper section of the drill stem is always cleaned when a new drill stem section is added.

I claim:

45 1. Cleaning apparatus for cleaning tubular drill stems of a rotary drill, the drill having a drill head adapted to be secured to an upper end of an uppermost drill stem section and having a fluid passage through which drilling fluid is pumped into the drill stem, the cleaning apparatus including:

- 50 a. a tubular scraping member adapted to have a sliding fit in the drill stem,
 b. a cable secured at one end to the scraping member and at an opposite end to the drill head so that the

- scraping member is freely suspended in the drill stem and movable upwards therethrough to scrape the stem whenever the drill head is detached from an upper end of the drill stem to add a new drill stem section thereto,
- c. a screen secured to the scraping member for receiving material removed from the drill stem.
2. Cleaning apparatus as claimed in claim 1 in which the scraping member is bevelled at an upper edge to provide a knife edge.

3. Apparatus as claimed in claim 1 in which length of the cable is such that when the drill head is connected to an uppermost drill stem section the scraping member is suspended above a lower end of the uppermost drill stem section.

4. Apparatus as claimed in claim 1 in which the scraping member has a transverse connecting bar extending diametrically thereacross for securing the member to the cable.
